UNITED STATES PATENT OFFICE

ARTHUR HOUGH, OF PASSAIC, NEW JERSEY

CONCENTRATING AND BLEACHING SULPHURIC ACID

No Drawing.

Application filed January 11, 1930. Serial No. 420,284.

The present invention relates to concentration and bleaching of sulphuric acid containing carbonizable organic matter, and more particularly to sulphuric acid which has been used for the parchmentizing of paper or waterleaf.

Whereas, my invention can be applied to sulphuric acid containing many kinds of organic matter, which can, by the application of heat be decomposed and carbonized, the invention will be described here as it relates to the bleaching of sulphuric acid from parchmentizing processes.

In making "vegetable parchment" the waterleaf paper is passed through a bath of cold sulphuric acid (for example sulphuric acid of about 68 to 73% strength, and preferably between 70% and 71% strength) at temperatures of about 50 to 60° F. The sheet being treated may conveniently be a 23 pound paper or a 25 pound paper, and preferably a paper which is somewhat porous. The parchmentized paper is then washed with cold water or with cold dilute acid and then with cold water, until the paper is substantially free from free acid, after which the paper is dried and subsequently rolled up or cut into sheets of the desired size. The dilute sulphuric acid, forming a by-product is, in some plants, reconcentrated for reuse in the parchmentizing process.

During the process of parchmentizing paper or waterleaf some of the surface fibres of the paper are, by the action of the machinery and acid, removed from the surface of the paper into the sulphuric acid of the parchmentizing bath or into the washing bath, and these fibres having been parchmentized with the paper from which they are detached, constitute what is known in the art as "fuzz" or "amyloid", and during the concentration of the sulphuric acid, this "amyloid" or "fuzz" together with any organic matter dissolved by the acid, is wholly or partially decomposed, which blackens the acid, rendering it unsuitable for parchmentizing further amounts of paper, if the best results are desired. This black color must therefore be removed.

Bleaching of the acid has heretofore been

accomplished by one of several reagents such as permanganate or bichromate or the like. The use of such oxidizing agents however results in the formation of sulphates which rapidly load up the acid to the point where considerable quantities of these sulphates are present in the acid, and these may deposit in the pipe lines and equipment employed in the factory, causing trouble, delays and expense.

Sulphuric acid from the parchmentizing machines may be reclaimed at around 25% strength and if this is concentrated up to about 70% H_2SO_4 at atmospheric pressure, then the temperature and time factors will be such as to almost completely decompose the "amyloid", and the acid may leave the concentration apparatus at 130 to 150° C., and can be run into the bleaching tank without any further heating. If however, the weak acid be concentrated to around 70% H_2SO_4 at reduced atmospheric pressure (i. e. under vacuum), then it is advisable to raise the temperature of the 70% acid to about 140 to 150° C., by any suitable means and hold it at this elevated temperature, preferably while undergoing agitation, until the "amyloid" is wholly or sufficiently carbonized to respond well to the bleaching treatment.

In some instances sulphuric acid is reclaimed from the parchment machines at a strength little below that required for parchmentizing, and by the simple addition of a high strength acid such as oleum of selected strength, to compensate for the amount of acid lost in process, the sulphuric acid will be strong enough to employ again for parchmentizing the paper. It will however still contain "amyloid" and this must be carbonized and bleached out, otherwise the acid would eventually become loaded with the "amyloid" and useless. To prepare such an acid for bleaching it is only necessary to hold it in a suitable vessel containing heating units, or heated from the outside by means of a steam or hot oil jacket, or any suitable method, and preferably agitate the acid in order to secure the carbonized amyloid in an extremely fine, almost colloidal condition, which condition is admirable for subsequent

bleaching by the method described below. In this way, after a time it will be found that the amyloid will have decomposed and the acid will be quite black.

- 5 In accordance with the present invention I employ ammonium nitrate either in the crystallized state or preferably in solution in water. If the crystals are used, these must be put into the black acid in calculated quantities, and to get the best results, brisk agitation of the acid by mechanical or other means should be continued until the desired degree of bleaching is effected.

If a solution of ammonium nitrate is used (and this is the preferred way to use it) the warm concentrated solution may be run into the black acid, preferably mixing with it in the stream running from the concentrator, or in the case of no concentration of the acid being required, from the apparatus employed for carbonizing the "amyloid". This solution, (which may for example be 70 to 80% strength) may be fed (say, at 60 to 80° C.) from an elevated tank or it may be forced by means of a suitable pump well down into the black acid which effects good mixing.

I preferably provide an acid-proof box having considerable depth, and the hot acid from the concentrator runs into the lower part of this box through a glass tube. I also provide a separate glass tube for delivering ammonium nitrate solution into close proximity to the stream of acid running from the concentrator into the said box. The box may be kept at about 145° C. or at any event should be kept sufficiently hot to cause the sulphuric acid to immediately react with the ammonium nitrate, and give off nitric acid which in the nascent state at once attacks and destroys the carbonized organic matter in the acid.

The flow of ammonium nitrate solution will of course be regulated to suit the condition of the black acid, i. e. the amount of organic matter therein contained to be oxidized, or bleached out. On addition of the ammonium nitrate whether in the form of crystals or solution, the reaction is as follows:

This reaction is fairly rapid, but the actual bleaching effect is not so rapid, depending largely on the temperature. It is therefore necessary to maintain the acid at as high a temperature as is convenient, which of course may be done by inserting a heating coil, which may be of lead, in the acid tank and employing steam or heated oil or any suitable heating medium for this purpose. It is not advisable to use too much heat for this purpose, as some of the available nitric acid (resulting from the reaction of the ammonium nitrate with the sulphuric acid may be driven off reducing the efficiency of the proc-

ess). The best temperature for this system of bleaching is around 140° C. for acid at about 70% H_2SO_4 .

The time required under such conditions for a good end point in color, which is a light amber tint, is about 20 minutes, so if a continuous process of bleaching is desired the capacity of the black acid tank should be regulated to this end. The acid having been bleached, it is now necessary to remove the excess of nitric acid, and the ammonium sulphate shown in the above equation. This removal is brought about automatically and without any additions of chemicals of any nature, only if the reaction is desired to be speeded up it is best to raise the temperature of the bleached acid as high as possible, which of course can only be as high as the boiling point of the acid, which if 70% is around 170° C. and it is advisable to keep the acid agitated during this process of denitrification. Agitation by bubbling a regulated air current through the acid is good. A convenient way to do this is to have a second tank into which the bleached acid flows, this second tank having a separate heating coil employing any suitable heating agent capable of keeping the bleached acid at the desired high temperature. Under these conditions another reaction proceeds, which may be expressed as follows:

The entire series of reactions occurring may be somewhat complicated, but the above equation expresses the result briefly. Experience has shown that the process results in very good bleaching, and the final outcome is bleached acid without a trace of nitric acid or low oxides of nitrogen or ammonium sulphate present, all accomplished by the addition to the black acid of one reagent only, and that is ammonium nitrate. This reagent moreover does not add salts in the form of sulphates to the bleached acid, for the reasons above described.

The quantity of ammonium nitrate solution employed will depend upon the degree of blackness of the acid, and this in turn will depend upon a good many factors in the parchmentizing and washing processes. In a factory where 100,000 pounds of 70% bleached acid are made from waste dilute acid (about 20% strength) each day, the amount of ammonium nitrate may be from 100 pounds to 500 pounds, depending upon the blackness of the acid. The pump for introducing the ammonium nitrate solution is preferably adjustable so that it can be run faster or slower, or so that the stroke of the pump can be made greater or less, in order to deliver the best amount of ammonium nitrate solution into the sulphuric acid to be bleached.

The removal of the free nitric acid and

low oxides of nitrogen is absolutely essential when the bleached sulphuric acid is to be again employed for parchmentizing paper or waterleaf. If they are not removed, the 5 product referred to, viz., parchment paper will be of inferior quality due to the action on the paper (cellulose) by nitric acid.

I have above referred to concentrating the acid to about 70% strength before bleaching.

- 10 In some cases it may be more advisable to concentrate to a somewhat lower degree than this, and then effect bleaching by the process above described, followed if desired, by further concentration. In most cases however 15 I prefer to carry the concentration to a little above the concentration which is to be used in parchmentizing, since the sulphuric acid may become diluted a little during the bleaching operation, by the water constituting the 20 solvent of the ammonium nitrate and the water produced in the decomposition of the ammonium sulphate.

It will be understood that the reaction between sulphuric acid and ammonium nitrate, 25 to form nitric acid occurs at all temperatures, but the secondary reaction between the ammonium sulphate and nitric and nitrous acids requires relatively high temperatures.

I have referred above to adding the solution 30 of ammonium nitrate while warm. The solution can be added cold, if desired. Ammonium nitrate solution when warm, will hold more of the nitrate, so that less water need be added if the solution is used warm.

35 I have referred to introducing this through a glass tube. A porcelain or earthenware pipe or tube can be used, but glass is transparent.

Having described my invention, I claim:

40 1. A process of concentrating and bleaching sulphuric acid containing organic matter, which comprises concentrating the acid and adding ammonium nitrate, and holding the acid hot until the acid is bleached, substantially as described.

45 2. A process of concentrating and bleaching sulphuric acid containing carbonized organic matter resulting from the carbonization of degradation products of cellulose, which 50 comprises concentrating the acid by heating to at least 70% strength, and adding to the hot acid a solution of ammonium nitrate, substantially as described.

55 3. A process of concentrating, bleaching and denitrating sulphuric acid containing organic matter, which comprises concentrating the acid by heating to not substantially below 70%, adding ammonium nitrate, and holding the bleached acid hot long enough to 60 bring about the reactions between nitric acid and nitrogen oxides and ammonium sulphate, resulting in a denitrated bleached acid, substantially as described.

65 4. A process of concentrating, bleaching and denitrating sulphuric acid containing

organic matter, which comprises concentrating the acid to a strength sufficient for use in parchmentizing, adding ammonium nitrate in solution below the surface of said acid, holding the acid hot until bleaching 70 is brought about, agitating the acid during the addition of ammonium nitrate solution, then raising the temperature of the bleached acid to bring about more rapidly the secondary reaction resulting in denitration of the 75 sulphuric acid substantially as described.

5. A process of bleaching sulphuric acid containing organic matter, which comprises heating the sulphuric acid long enough to at least partially decompose and carbonize such 80 organic matter to put it in condition to respond to the bleaching process, then adding ammonium nitrate, keeping the acid sufficiently hot for sufficient time to sufficiently bleach the acid, and to denitrate the same 85 substantially as described.

6. A process of concentrating and bleaching the dilute sulphuric acid remaining from parchmentizing and similar operations containing degradation products of cellulose, 90 which comprises concentrating the acid to about 70% H_2SO_4 whereby a considerably blackened acid is produced, adding to said acid, while hot, a solution of ammonium nitrate and heating the acid to aid in decomposing the ammonium nitrate and blowing with air to remove the last of the nitric acid 95 liberated.

7. In concentrating and bleaching dilute sulphuric acid from parchmentizing and similar operations, containing degradation products of cellulose, the herein described steps of adding a solution of ammonium nitrate to the hot concentrated dark colored sulphuric acid, and supplying heat to the 105 acid.

8. In the process of claim 7, introducing the dark colored concentrated acid into a bath of such acid, while the latter is hot, and introducing a solution of ammonium nitrate, 110 such two introductions being effected in close proximity to each other, whereby they mix promptly.

9. Process as in claim 7, in which the concentrated acid and the nitrate solution are 115 both introduced at near the bottom of the bath of acid.

10. A process of bleaching sulphuric acid containing organic matter, which comprises heating the acid long enough to ensure decomposition of the organic matter, adding ammonium nitrate, holding the acid at a temperature and for a length of time necessary to sufficiently bleach the acid, then raising the temperature of the acid to accelerate the 120 secondary reaction to produce denitration, substantially as described.

11. A process of recovering sulphuric acid of a concentration adapted for parchmentizing which comprises heating the reaction 125

product of ammonium nitrate and 70% sulphuric acid containing carbonization products of cellulose, at about 145° C., long enough to bleach out the organic matter and raising the temperature of the mixture to 170° C., so as to effect the decomposition of the ammonium sulphate.

5 In testimony whereof I affix my signature.
